ABSTRACT OF THE DISCLOSURE

This disclosure relates to pail tapering and flanging tools wherein an upper supporting member is moved telescopically into a generally right circular cylindrical pail carried by a lower supporting member, the upper supporting member having tapering members mounted at at least one end thereof for transmitting tapering forces to the pail. The tapering members may be fixed, or may be rollers, and may be mounted at both ends thereof. Additionally, the tapering members may be mounted for radial movement at one end thereof, for progressive tapering. Flanging wheels are provided for curling an upper portion of the pail, and a beading tool is also provided, associated with the lower support.

The present invention relates to a method of producing a novel conical pail and to machine structures for carrying out the method.

There has long been a desire to produce conical pails rapidly and inexpensively. Pails conical in form are very desirable because a supplier can deliver such pails to consumers in stacked relation, or in other words in nested relation. In this way, the space or volume required in the transporting of the pails to the consumers is greatly reduced.

The conical pails which have hitherto been manufactured have, as a rule, been produced in such a way that body blanks having arced upper edges and arced lower edges and with straight converging side edges have been stamped out of a plate. When side edges are joined to each other in forming a side seam, a tapered body is obtained, to which a bottom is thereafter seamed. This procedure can result in provision of very good pails, but the cost of thus producing the tapered bodies is unnecessarily high, due to the fact that special stamping tools must be used for stamping out the bodies and, moreover, stamping with said tools causes waste of material.

The purpose of the present invention is to provide a novel method the practicing of which will bring about a considerable cheapening in the production of the tapered bodies. According to the invention, this is achieved by using a plurality of rectangular body blanks, which may be fabricated to provide one or more cylindrical tubes. Each such tube is thereafter inserted in a machine so that the tube, through the machine, can be expanded or reshaped to become conical, or rather frusto-conical in form. Before or after said expansion, the tube is provided with the usual bottom, through seaming or other means of attachment.

According to the invention, the expansion of the tube can take place in such a way that the bottom end of the tube is secured in a suitable member in said machine, and said machine has a forming tool which is inserted in the tube, provision being made for bringing about relative rotation between the tool and the tube.

According to a special design of said tool, the forming or shaping means can consist of a number of cylindrical members, arranged in a ring, and which can be fixed or movable in the tool, the axes of said members converging toward a common point.

According to a further design of the invention, the tool can be provided with members which cause the upper edge of the tube to be rolled over or curled.

Another object of the invention is to provide a novel method and apparatus for forming pail bodies of the character stated wherein the shaping members, when fixed are arranged on a carrier with their axes converging toward a common point, the carrier and members being progressively movable into the pail blank while relative rotary movement is being brought about between the blank and said carrier and member assemblies.

Another object of the invention is to provide a method and apparatus of the character stated wherein the forming or shaping members when movable in the tool comprise a plurality of rotary members generally cylindrical in form and having fixed bearings at the ends thereof disposed initially to enter the pail during a tapering action, and movable bearings at their other or outer ends which can be progressively spread apart during the progression of the tapering operation.

Yet another object of the invention is to provide a method and apparatus of the character stated wherein internal or external beading may be provided in the pail during the bringing about of the relative rotary movement of the tool or apparatus and the pail.

Still another object of the invention is to provide a novel pail structure formed by practicing of the above mentioned methods and by use of the mentioned apparatus.

With the above and other objects in view that will hereinafter appear, the nature of the invention will be more clearly understood by a reference to the following detailed description, the appended claims and the several views illustrated in the accompanying drawings.

In the drawings:

FIGURE 1 is a central vertical sectional view, partly in elevation, showing a tool including rotary shaping members in the process of progressively tapering a pail.

FIGURE 2 is a sectional perspective view illustrating another form of tapering tool or apparatus wherein provision is made for moving the trailing ends of the rotary shaping members outwardly and inwardly relative to the leading ends of said members.

FIGURE 3 is an enlarged fragmentary sectional view illustrating one of the movable bearings of the tool of FIGURE 2 and the means for bringing about the movement of said bearing.

FIGURE 4 is a central vertical sectional view, partly in elevation, showing the tool of FIGURES 2 and 3 inserted in a pail preparatory to the outswinging of the upper ends of the rotary shaping members and tapering of the pail.

FIGURE 5 is a perspective view illustrating another form of the forming or shaping tool wherein the circumferentially spaced tapering members are cylindriform in shape and fixedly suspended from the rotary carrier with their axes converging downward toward a common point.

FIGURE 6 is a side elevation illustrating a pail beading apparatus including beading rolls engageable with a pail for circumferentially beading the same.

In FIGURE 1, a cylindrical tube 1 is shown, at the lower end of which a bottom 2 has been secured, as by seaming or in any approved manner. The bottomed pail blank or tube is secured on a carrier or holding member 3 by any approved means (not shown), and said carrier can be either fixed or arranged for rotation about its vertical axis. Around the same vertical axis, a rotatable shaft 4 is arranged, and this shaft is provided with two circular disks 5 and 6. There is a spacing member 7 between the disks, and the disks carry between them a number of rotatably supported rollers 8, which rollers are arranged with their axes in a circular ring set at an angle or con-

verging slightly toward the common axis of the shaft 4 and spacer 7 in such a way that the taper desired for a pressed out pail is obtained. Around the edge of the upper disk 5 a number of wheels 9 are arranged. The wheels have the shaping profile shown in the drawings, and when forced downward against the upper edge of the tube 1, serve to roll over or curl said edge.

The tool or apparatus thus described functions in the following way. A cylindrical tube 1 with its bottom 2 is fastened in the holding member 3. In this example description it is assumed that the holding member 3 does not rotate around its axis. In this situation, the forming tool parts 8 and 9 are inserted vertically downward through the upper opening of the tube 1 while the tool rotates around the axis of its shaft 4. During the insertion, the body of the tube 1 will successively be expanded so that, when the tool has been inserted completely, the taper desired of the tube 1 will be obtained, and during the last part of the insertion, the upper edge of the tube will be bent over or curled by engagement therewith of the wheels 9.

In FIGURES 2-4 a tool is shown which differs from the tool of FIGURE 1 in that the rollers 8' are supported in such a way at their upper ends that the bearing parts can be displaced radially. Through this displacement, the rollers can be made to assume two different end positions, one a retracted position in which the tool can be readily inserted in a tube or pail blank without changing the form of the tube. In this case or position, in rotation of the tool the forming parts 8 describe a surface of rotation which is cylindrical in character. See FIGURE 4. In the other case or position, the rollers 8', when moved out at their upper ends as indicated by the arrows in FIGURE 4, assume such a position that they achieve the tapering desired.

In FIGURE 2, the rollers 8' and the mountings therefor are clearly shown. The bottom plate 6' supports the lower ends of the rollers 8' on fixed pivots. The spacing member 7 is shown, as is the driver shaft 4'. The shaft 4' is hollow and in its cavity is mounted an axially movable rod 10 which has a tapered end 11. The upper ends of the rollers 8' are supported in bearing parts 12 which are radially movable in radial recesses in the upper disk 5' of the tool. In order to prevent the bearing parts from leaving the grooves radially, the disk 5' is provided with two peripheral retainer or spring bands 13 and 14, each including spring hump portions S engaged with the respective bearing blocks 12. Each bearing block 12 is moreover provided with two strips or keys 15 and 16, extending in a radial direction and which coact with grooves 17 and 18 in the disk 5', thereby to prevent the bearing parts 12 from moving axially. There are radially movable cylindrical thrust members 19 reciprocable in radial holes provided in the disk 5' as clearly shown in FIGURES 2 and 4. Each member 19 coacts at one of its ends with the tapered surface 11 on the rod 10 and at its other end with the respective bearing part 12. The bearing parts 12 are kept pressed against the cylindrical members 19 with the aid of the bands 13 and 14. In FIGURE 3, the coaction between the rod 10 with the tapered surface 11, the cylindrical members 19 and the bearing parts 12 is clearly shown.

The tool of FIGURES 2 and 4 last described functions in the following way. A tube 1' with a bottom 2' is secured in a holding member 3'. In the present case, it is assumed that the holding member 3' is not rotatable around its axis. In this condition, the tool with the cylindrical rollers is inserted in the tube 1' as shown in FIGURE 4. When the tool has thus been inserted completely, it is caused to rotate, while at the same time the rod 10 is moved downward. Owing to the fact that the rod 10 has a tapered surface at its lower end, the cylindrical members 19 will be moved outward radially, causing the bearing parts 12 also to be moved outward in a radial direction, so that the rollers 8 will be forced to assume

the inclination desired, and the tube 1' will thus be given the taper desired. Also this tool can be provided with the same kind of wheels 9 as shown in FIGURE 1 if desired.

In the last-mentioned design of the tool it has been shown that only the upper bearing parts for the rollers are to be movable radially. However, it should be apparent that the bearing parts for the lower ends of the rollers 8' may also be arranged in such a way that they also are movable radially, if desired. It will also be apparent that rotation could be imparted to the holder 3', as indicated by the applied arrow, while the inserted tool other than the rod 10 is held stationary, should this be desired.

In FIGURE 5, a third design of a forming tool is shown. This tool has a shaft 4" and a disk 5". However, there is no lower disk 6 and spacing member 7 in this form. Instead of rollers 8, the disk 5 is provided with a number of cylindrical members 8", which are secured in such a way that if a surface is laid through the longitudinal axes of said members, a taper will be formed, which has the same cone angle as a formed pail is to have. The previously mentioned wheels, by means of which the upper edge of the tube is to be rolled over, are arranged at 9" on the disk 5".

The tool last described functions in the following way. A cylindrical tube 1 with a bottom 2 is secured in the same way as previously mentioned in a holding member 3, which is not rotatable, all as shown in FIGURE 1. This tool, while rotating around its axis, is inserted in the tube thus secured, and during the progressive insertion the tube will be given the taper desired. During the last part of the insertion, the upper edge of the tube will be rolled over by means of the wheels 9", as previously described.

It is preferred that the body plates from which the pail bodies are formed are made of the usual metallic materials, and have thicknesses of between 0.2 and 0.5 mm.

In FIGURE 6, a tool 4", 5" is shown inserted in a tube 1"". The tool is caused to rotate, in any approved manner, not shown, while the tube is secured by means of any approved holder members also not shown. At the lower end of the tube, a tool for the forming of inward beads is arranged, which tool consists of two forming members 20 and 21, each arranged on an arm 22 and 23, respectively. Said two arms are fastened each on a double-armed lever 24 and 25, which are rotatably supported pivotally at 26 and 27. By imparting movement such as is indicated by the two arrows in FIGURE 6, to the levers 24 and 25, as by imparting a downward thrust at 28, and by causing the levers to rotate around the axis of the shaft 4", the members 20-21 will produce an inward bead. It should be obvious that multiple sets of forming members 20-21 can be arranged, so that the number of inward beads desired can be obtained.

In case outward beads should be desired, it will be necessary to provide the rollers 8 or 8' of the tools of FIGURES 1, 2 and 4 with the number of external peripheral welts or protuberances corresponding to the outward beads desired and to have outer forming members comparable to the members 20 and 21 of FIGURE 6 but made in such way that they coact with said welts.

While preferred method steps and part arrangements have been described in detail herein, it is to be understood that variations in said steps and part arrangements may be made without departing from the spirit and scope of the invention as defined in the appended claims.

I claim:

1. A tool for changing a pail body blank of generally cylindrical shape into a tapering body form, said tool comprising a supporting means having thereon a plurality of generally cylindriform shaping members arranged in a circle and presentable in a pail body blank with their axes converging toward a common point thereby to present shaping surfaces disposed to describe a frusto-coniform surface of rotation upon the imparting of rotation to the supporting means, means located at at least one end of each of said members mounting said members on said

supporting means for transmission of shaping forces to said members solely through said mounting means whereby upon insertion of the tool into a generally cylindrical pail body blank and the bringing about of relative rotary movement between the blank and the tool the blank shape will be changed to frusto-conical.

2. A tool structure for changing a pail body blank of generally cylindrical shape into a tapering body form, said tool comprising a supporting means having thereon a plurality of generally cylindriform shaping members arranged in a circle and presentable in a pail body blank with their axes converging toward a common point thereby to present shaping surfaces disposed to describe a frusto-conical surface of rotation upon the imparting of rotation to the supporting means, whereby upon insertion of the tool into a generally cylindrical pail body blank and the bringing about of relative rotary movement between the blank and the tool the blank shape will be changed to frusto-conical, wherein the supporting means also carries edge curling means engageable with top edge portions of a blank to form a curl on said edge portion during the relative rotation of the tool and blank and in conjunction with the reshaping of the blank.

3. A tool structure as defined in claim 1 wherein the shaping members comprise rotatably mounted rollers.

4. A tool structure as defined in claim 1 wherein the shaping members comprise rigidly mounted free ended pins.

5. A tool structure as defined in claim 1 wherein the supporting means also carries edge curling means engageable with top edge portions of a blank to form a curl on said edge portion during the relative rotation of the tool and blank and in conjunction with the reshaping of the blank and wherein the shaping members comprise rotatably mounted rollers.

6. A tool structure as defined in claim 1 wherein the supporting means also carries edge curling means engageable with top edge portions of a blank to form a curl on said edge portion during the relative rotation of the tool and blank and in conjunction with the reshaping of the blank and wherein the shaping members comprise rigidly mounted free ended pins.

7. A tool structure as defined in claim 1 wherein the supporting means also carries rotatably mounted edge curling disks engageable with top edge portions of a blank to form a curl on said edge portion during the relative rotation of the tool and blank and in conjunction with the reshaping of the blank.

8. A tool for changing a pail body blank of generally cylindrical shape into a tapering body form, said tool comprising a rotor, spaced disks traversing the axis of the rotor and movable therewith, and a plurality of rollers rotatably mounted at both ends and placed in a circle between said disks so that the outer portions thereof describe a frusto-conform surface of rotation upon rotation of said rotor, wherein means are included for changing the position of the roller axes so that they progressively change from a parallel relation to positions in which the outer portions of the rollers describe a frusto-conform surface of rotation upon rotation of said rotor.

9. A tool for changing a pail body blank of generally cylindrical shape into a tapering body form, said tool comprising a rotor, spaced disks traversing the axis of the rotor and movable therewith, and a plurality of rollers rotatably mounted at both ends and placed in a circle between said disks so that the outer portions thereof describe a frusto-conform surface of rotation upon rotation of said rotor, wherein means are included for changing the position of the roller axes so that they progressively change from a parallel relation to positions in which the outer portions of the rollers describe a frusto-conform surface of rotation upon rotation of said rotor, said last named means including radially shiftable bearings for the rollers at at least one end thereof, spring means for moving the shiftable bearings inwardly, and

an axially movable camming means for moving said shiftable bearings outwardly.

10. A tool for changing a pail body blank of generally cylindrical shape into a tapering body form, said tool comprising a rotor, spaced disks traversing the axis of the rotor and movable therewith, and a plurality of rollers rotatably mounted at both ends and placed in a circle between said disks so that the outer portions thereof describe a frusto-conform surface of rotation upon rotation of said rotor, wherein means are included for changing the position of the roller axes so that they progressively change from a parallel relation to positions in which the outer portions of the rollers describe a frusto-conform surface of rotation upon rotation of said rotor said last named means including radially shiftable bearings for the rollers at at least one end thereof, spring means for moving the shiftable bearings inwardly, and an axially movable camming means for moving said shiftable bearings outwardly, each said shiftable bearing having key means thereon slidable in key-way means in the disk on which it is mounted, and said position changing means comprising spring ring means surrounding the bearings in the disk on which they are mounted and holding them in place, and an axially shiftable taper-cam and radial actuator plungers engaged with said taper-cam and the bearings surrounded by the spring ring means.

11. A tool for changing a pail body blank of generally cylindrical shape into a tapering body form, said tool comprising a rotor, spaced disks traversing the axis of the rotor and movable therewith, and a plurality of rollers rotatably mounted at both ends and placed in a circle between said disks so that the outer portions thereof describe a frusto-conform surface of rotation upon rotation of said rotor, wherein means are included for changing the position of the roller axes so that they progressively change from a parallel relation to positions in which the outer portions of the rollers describe a frusto-conform surface of rotation upon rotation of said rotor said last named means including radially shiftable bearings for the rollers at at least one end thereof, spring means for moving the shiftable bearings inwardly, and an axially movable camming means for moving said shiftable bearings outwardly, each said shiftable bearing having key means thereon slidable in key-way means in the disk on which it is mounted, and said position changing means comprising spring ring means surrounding the bearings in the disk on which they are mounted and holding them in place, and an axially shiftable taper-cam and radial actuator plungers engaged with said taper-cam and the bearings surrounded by the spring ring means, said spring ring means including an inwardly bowed spring protuberance at the location of and engaging each of the bearings.

12. In apparatus of the character described for reshaping a generally cylindrical pail body, a tool with which the pail body is adapted to be brought into telescopic relation, and means on the tool for engaging in rolling contact with the body and effective during a bringing about of relative rotary movement between the tool and said body to form beading in said body.

13. Apparatus as defined in claim 12 wherein the reshaping beading means comprises at least two arms opposing and swingably mounted and carrying beading rollers engageable externally with the body, and means for swinging said arms to engage said rollers in beading contact with a pail body.

14. The herein described method of forming a tapered pail including the steps of providing a cylindrical body formed of a plurality of rectangular metal sheets, supporting the body at a lower closed end thereof by a lower supporting member, providing roller means mounted on an upper supporting member, moving the upper supporting member telescopically into the body relative to the lower supporting member, and engaging the body internally by the roller means in the form of a circle of

rollers presented to form a frusto-conical surface of rotation, thereby to change the shape of the body from cylindrical to frusto-conical.

15. The method defined in claim 14, wherein the presentation of the roller means is progressive along the axis of the body.

16. The herein described method of forming a tapered pail including the steps of providing a cylindrical body formed of a plurality of rectangular metal sheets, and engaging the body internally by roller means in the form of a circle of rollers presented to form a frusto-conical surface of rotation, thereby to change the shape of the body from cylindrical to frusto-conical, wherein the presentation of the roller means is by way of gradual outward tilting of the axes of the rollers from a generally parallel axis arrangement within the body to an arrangement in which said axes are relatively shifted to be included in said frusto-coniform surface of rotation whereby engagement of the rollers in and with the body during a bringing about of relative rotary movement between the body and the circle of rollers changes the shape of the body from cylindrical to frusto-conical.

17. The herein described method of forming a tapered pail including the steps of providing a cylindrical body formed of a plurality of rectangular metal sheets, and engaging the body internally by roller means in the form of a circle of rollers presented to form a frusto-conical surface of rotation, thereby to change the shape of the body from cylindrical to frusto-conical, wherein the presentation of the roller means is progressive along the axis of the body, and wherein coincidentally with the completion of the changing of the body shape to frusto-conical, edge curling rollers are presented against the open mouth defining edge of the body to outwardly curl the same.

18. The herein described method of forming a tapered pail including the steps of providing a cylindrical body formed of a plurality of rectangular metal sheets supporting the body at a lower closed end thereof by a lower supporting member, providing a circle of rigidly positioned free-ended pins mounted on an upper supporting member, moving the upper supporting member telescopically into the body relative to the lower supporting member, and engaging the body internally by the circle of rigidly positioned free ended pins presented to form a

45

frusto-conical surface of rotation, thereby to change the shape of the body from cylindrical to frusto-conical.

19. The herein described method of forming a tapered pail including the steps of providing a cylindrical body formed of a plurality of rectangular metal sheets, and engaging the body internally by a circle of rigidly positioned free ended pins presented to form a frusto-conical surface of rotation, thereby to change the shape of the body from cylindrical to frusto-conical, and wherein coincidentally with the completion of the changing of the body shape to frusto-conical, edge curling rollers are presented against the open mouth defining edge of the body to outwardly curl the same.

20. The tool structure as defined in claim 1, wherein said mounting means at the ends of said members alone connect said members to said supporting means.

21. The tool structure as defined in claim 20, wherein said mounting means are provided at both ends of said members.

22. A first tool as set forth in claim 1, in combination with and positioned for vertical movement relative to a second tool, with the pail body therebetween, and means on the second tool for engaging in rolling contact with the body and effective during a bringing about of relative rotary movement between the tool and said body to form beading in said body.
